UNITED STATES PATENT OFFICE.

GEORG GRABE, OF NIKOLASSEE, NEAR BERLIN, GERMANY, ASSIGNOR TO SIEMENS & HALSKE, A. G., OF BERLIN, GERMANY, A CORPORATION OF GERMANY.

TELEPHONE SYSTEM.

1,239,097.

Specification of Letters Patent.

Patented Sept. 4, 1917.

Application filed August 26, 1913. Serial No. 786,697.

To all whom it may concern:

Be it known that I, GEORG GRABE, a German citizen, and resident of Nikolassee, near Berlin, Germany, have invented certain new 5 and useful Improvements in Telephone Systems, of which the following is a specification.

My invention relates to that class of telephone systems in which automatic or semi-automatic devices are employed for first 10 establishing a preliminary connection between two points of a telephone plant and in employing thereupon other such means for establishing a talking connection between 15 said points over a shorter path, while the preliminary connection is released. More particularly my invention relates to the means of establishing the talking connection. My present invention considers 20 the establishing in any known manner of a preliminary connection and then the setting up of the switches of the second connection by impulses sent out from a point of the preliminary connection, the number 25 of said impulses corresponding to the points to be connected by the talking connection.

The specification of my invention refers to a system in which talking connections for long distance conversations are to be 30 established. I wish it understood, however, that the invention be not restricted to long distance conversations but that the talking connections may also join subscribers of a local office or offices.

35 My present invention also refers to details of establishing the talking connection as will more clearly appear with reference to the descriptions.

Referring now to the particular application 40 of my invention to long distance connections I employ selectors of a construction as used for local service also for making long distance connections. This is accomplished by connecting the long distance line 45 with a line for local service made busy over a selector or multiple contact (subscriber selector or multiple contact for subscriber selectors) by a back-selecting circuit from any desired point of the connection (subscribers 50 station or operator's place) which is possible over selectors which are controlled from the trunk line office by an additional combination of current impulses.

To provide special circuits for the long 55 distance service results in special advan-

tages. If in a local office with 5000 subscriber connections there be, for instance, 500 groups each having ten line selectors and 100 connections for long distance service, then, for establishing a long distance 60 connection it would be necessary to use first, second and third group selectors in order to reach a line selector. According to this invention, now, in the circuit leading over these group selectors only one preliminary 65 connection with the line selector or with the desired subscriber line itself is established. From the place thus reached a circumventing connection will then be made which for the aforesaid example will only 70 require a so-called hundred-system, as only one of the 100 long distance connections has to be chosen. The circumventing connection in this circuit is therefore shorter than the preliminary connection. 75

According to this invention the preliminary connection contains only those switching instrumentalities which prepare a subscriber selector for the long distance service, while the switching instrumentalities 80 for properly establishing the long distance connection are advantageously associated with the circumventing connection, because in this case the selectors of the longer preliminary connection which have been in use 85 only for a short time may again be made free for making other connections.

Still another advantage results from the employment of special switching connections for long distance service, namely the 90 possibility of using an improved line construction such as by employing heavier copper strands or by addition of Pupin coils. In case local and long distance service were united throughout the system, all connecting lines between the local offices would have to be made of superior construction, while by having separate connections such superior construction may be limited to long distance connections. On the other hand 95 the same subscriber selectors may always be employed for either mode of operation; for in this case the subscriber lines are connected to these selectors, which lines do not need to be changed for long distance service. The 100 employment of special switching connections for the long distance service by commonly using the subscriber selectors provided for local service will therefore allow not only the smallest number of lines to be 110

employed but also the smallest number of subscriber selectors.

While it is not necessary to connect the special switching connections with the ordinary switching connections at the very point where the improved line construction ends, it may be found advantageous by considerations other than those of line construction, to have the switching connections run parallel to each other on a still further part of the line.

In case, for instance, the lines coming in at a smaller office from the main office, end at the latter office in two group selectors, then the long distance connections up to these selectors would have to be kept separate from the lines for local connections, while the sets of contacts for the second group selectors could be switched together. In view of possible later arrangements of the long distance system it would further be desirable to provide also special third group selectors; in every case, however, both kinds of switching connections must be led to the same subscriber selectors.

My invention will be more fully understood by reference to the accompanying drawings which show the arrangements according to my invention only in a diagrammatic manner, details such as circuits for switching, testing, separating or other purposes being not fully shown. In the drawings, Figure 1 shows a system in which upon taking off the receiver, a first and a second pre-selector will adjust themselves in succession upon the line calling, whereupon by means of current impulses from the calling station the adjustment of a first, second and third group selector and a line selector is accomplished to connect to the desired subscriber line, Fig. 2 shows the details of a long distance group selector used in the arrangement of Fig. 1 and its set of relays, Fig. 3 shows other details of the connections of Fig. 1, Fig. 4 represents diagrammatically the circuits for a long distance connection, and Fig. 4^a another manner of arranging said circuits, Fig. 5 the circumventing connection forming a preparatory circuit for the long distance connection, Fig. 6 an arrangement of this kind whereby only one place with apparatus for sending impulses is provided for several long distance stations. Fig. 7 shows a connection of a numeral sender's place over selectors with subscribers of the local office in which pre-selectors are associated with the subscriber lines. Fig. 8 shows a similar arrangement in which each pre-selector of a subscriber is provided with a resistance and a special switching lever in addition to the testing or separating relay and the call relay. Fig. 9 shows in a diagrammatic way a long distance telephone system with local subscribers differing from that of Fig. 8 in

that the local subscriber lines are connected at the local office to call seeker contacts and led over first and second call seekers, and Fig. 10 shows details of the connections of the arrangement according to Fig. 9.

70

Similar reference characters designate similar devices throughout the drawings; also for the sake of clearness in the figures showing details of the connections I have indicated the relays by capital letters, while the contacts of these relays are designated by means of corresponding small letters, and the reference numerals. Furthermore all switching instrumentalities are shown throughout the drawings in their position 75 of rest.

80

Referring now more particularly to the drawings, in the system of Fig. 1 the connection between two subscribers T_1 and T_2 is made in such a way that in taking off the receiver at the calling station T_1 , a first pre-selector VW , and a second pre-selector VW_2 will adjust themselves in succession upon the calling line, whereupon by a combination of current impulses through numeral impulses sent from the subscriber station T_1 , the adjustment of the group selector I.GW, II.GW and III.GW and the line selector LW will be established upon the line of the desired subscriber T_2 . These selectors may be constructed according to the well known Strowger type. At F I have indicated a subscriber to a trunk line office which may be connected to the local line over a third group selector III.GWF which is only accessible from the trunk line office. At the selector III.GWF a set of relays indicated by RS is provided by means of which the specific switching operation for long distance connections are effected.

95

The long distance group selector III.GWF and its associated set of relays RS of Fig. 2 and the details of the connections of the line selector LW which is connected to the selector III.GWF of Fig. 3 will operate as follows: For making a connection over the selector III.GWF and LW at the subscriber station F of the trunk line office a ground connection is made on the line c , whereby at the group selector III.GWF the relays C_1 , E and B_1 will respond in the following circuits: First—ground made at the trunk line office, line c , head contact k_1 , winding 1 of C_1 , winding 1 of E , battery and ground; Second—ground at the trunk line office, line c , head contact k_2 , winding 1 of B_1 , battery and ground. The relay C_1 which inserts itself over its contact 10 and the shaft contact wk_1 into a circuit which is independent from k_1 connects the impulse relay A_1 over contact 11 with the line a and also the winding 2 of the relay B_1 with the line c' . As B_1 has already responded over its winding 1 and over the line c and closed the contact 13, the winding 2 of B_1 is also connected to the

100

120

125

130

line *b* over 12' and 13. Relay *B*₁ furthermore has closed its contacts 14, 15, 16 and 18 and opened its contact 17. *C*₁ has also closed its working contact 19 and thereby prepared the circuit for the rotary magnet *D*₁.

In connecting relay *A*₁ with the line *a* and the winding 2 of the relay *B*₁ with the line *b*, these relays were excited because at the trunk line office the line loop *a*, *b* had been closed or because at *a* and *b* corresponding potentials had been impressed. Thereupon without interrupting the excitation of the relay *B*₁ over the line *a* from the dial switch of the long distance subscriber current impulses are sent which act upon the relay *A*₁ in such a manner that this latter becomes electrically inoperative at each current impulse, thereby closing its contact 20. As contact 18 of *B*₁ is closed at each current impulse the lifting magnet *H*₁ will be excited over the ground, battery, *H*₁, 20, 18 and ground, said lifting magnet *H*₁ lifting at each current impulse the switching axle of the selector III.GWF by one step. At the first step the contacts *k*₁ and *k*₂ of the head switches will be opened and contact *k*₃ will be closed. After the last lifting impulse the circuit for both relays *A*₁ and *B*₁ will be interrupted until at the beginning of the immediately succeeding series of impulses, by having the line loop at the trunk line office closed, or by having the respective potentials impressed upon lines *a* and *b* switched off. The relay *B*₁ which will be switched off at 13 after being no more excited from the *b*-strand and which remains connected to the line *c'* over 12' thereby closes the contact 17, so that now, since *C*₁ is excited, the rotary magnet *D*₁ receives periodically interrupted current impulses over ground, battery, 19, 17, *k*₃ and ground, thereby rotating in steps the switching axle of the group selector III.GWF. At the first step the axle contact *wk*₁ will be opened and *wk*₂ will be closed. By this, now, as *B*₁ is no more excited, and its contact 16' closed, the relay *C*₁ will be connected with both windings 1 and 2 over contacts 10, 16' and *wk*₂ with the line *c*. Now upon rotation of the switching axle the switching arms of the same will make connection with a free line selector, for instance, *LW* of Fig. 3, the following circuit will be established: ground, winding 2 of *B*₁, contact 12', line *c'* and *c''*, to the line selector *LW* in Fig. 3, contact 21 of relay *F*, winding 1 of a relay *C*₂, head contact *k*₄, battery and ground. In this circuit the relay *B*₁ at the group selector III.GWF and *C*₂ at the line selector *LW* will respond. *B*₁ again will close its contact 16 and therewith connects its windings 1 and 3 over 16 and *wk*₂ to the line *a*, so that *B*₁ after being excited over its winding 2 will now also be further kept excited over its windings 1 and 3 and line *a*. As

*B*₁ by reason of the latter excitation has opened contact 16', therewith the circuit of relay *C*₁ had been interrupted, and the latter deenergized, its operation now being taken up by the relay *B*₁. This operation consists therein that the circuit for the release magnet *M*, ground, battery, 17, 19', *M*₁, battery and ground, which circuit is closed by closing of the contact 19' of *C*₁, will simultaneously be kept open at 17 by the relay *B*₁. The relay *B*₁ has also its contacts 22, 23, 24 and 25 closed at the set of relays *RS* in Fig. 2 and therewith the testing of the desired line has been prepared from the trunk line office. By deenergizing *C*₁ and closing the contact 12, the winding 2 of relay *E* will be connected to the line *c'* over the contact 15 which is closed by relay *B*₁. As relay *E* is already excited by its winding 1 being in circuit of the relay *C*₁ which had already been energized together with the latter and its contact 26 open, then after the contact of the testing lever of the group selector III.GWF and after the deenergizing of the relay *C*₁ also the winding 2 of *E* will be connected to the line *c'* and therewith the excitation of *E* will be further maintained by having the contact 26 open after the interruption of the circuit for winding 1 of *E*. As the contacts 27 and 28 of relay *E* will remain closed after adjustment of the group selector III.GWF by having the potentials impressed upon the lines *a* and *b* at the long distance station, the circuits for the relays *A*₂ and *B*₂ of the line selector *LW* will be closed over the contacts 27 and 28. This is due to the fact that the relay *C*₂ has been excited after contacting with a free line selector and thereby closed the contacts 29, 30, 31, 32, 33, 34 and 36' and opened the contacts 35 and 36. By closing 29, for a retarding relay *V* over the winding 1 therefore the following circuit has been established: ground, battery, 29, winding 1 of *V*, axle contact *wk*₃ and ground. In this circuit *V* will respond and close its contacts 37, 38 and 39. At 37 and 38 relays *A*₂ and *B*₂ are connected to the lines *a''* and *b''* and excited over ground at the trunk line office, line *a*, 14, 27, *a''*, 37, *p*_v, winding 1 of *A*₂, 34, battery, ground, or ground at the trunk line office, line *b*, 13, 28, *b''*, 38, winding 1 of *B*₂, 44 and ground. The relay *V* further will close its contacts 39 and 40 so that its winding 1 will still remain excited over 39 and the contact 41 of *B*₂ if *wk*₃ is opened. The relay *B*₂ upon being excited has closed over contact 42 the excitation circuit for a relay *U* over ground, axle contact *wk*₄, winding 1 of relay *U*, contact 42, head contact *k*₅, battery and ground. The relay *U* upon being excited will close at contact 43 the circuit for the lifting magnet *H*₂ of the line selector *LW*, the circuit being ground, battery 31, *H*₂ 43, 46, *wk*₅ and ground. Fur- 130

thermore the relay U will open at 44 the circuit for the relay B₂, the latter, however, remaining further excited over its contact 45. If now again a series of impulses is sent 5 from the numeral sender of the long distance subscriber station into the line a, the latter by means of the relay A₂ will act over contact 46 upon the lifting magnet H₂. The latter now will lift the switching axle 10 of the line selector LW by a number of steps corresponding to the given number of current impulses. At the first step the head contacts k₄ and k₅ will be opened and k₆ and k₇ closed. The relay C₂ will remain in its 15 working position, upon k₄ being opened, over its contact 33, battery and ground independently of k₄ and after opening of k₅ the winding 1 of the relay U will be further kept excited over its contact 47 independ- 20 ently from k₄.

After completion of the lifting impulses for the line selector LW neither relay A₂ nor B₂ is excited for a short time and they will then simultaneously release. The relay 25 C₂ and E thereby will remain excited by the circuit over ground, battery, 33, windings 1 and 2 of C₂, 21, 49', 48, 32, resistance w and ground or c'', c', 12 winding 2 of E, 15, ground, the resistance 'w' being so di- 30 mensioned as to prevent the releasing of E. At the contact 42 of the relay B₂ the current passing through winding 1 of relay U will be interrupted. This relay becomes in- 35 operative and therewith closes its contact 43', while 43 will be interrupted so that thereby reversing from lifting magnet H₂ to rotating magnet D₂ will take place.

Thereupon A₂ and B₂ will again be excited from the long distance subscriber station. 40 Now, the given current impulses act also over the line a, a'' upon the relay A₂, while relay B₂ is being energized. These impulses will be transmitted in succession from the relay A₂ by opening the contact 46, over contact 43' to the rotary magnet D₂, 43', 46, wk₃ and ground. At the first step of rotation the axle contacts wk₂ and wk₄ will be opened. The circuit passing over wk₃ for the relay V and the rotary magnet D₂ will thereby be 45 interrupted, both, however, will further remain excited over the contacts 41 and 39 and ground. After completion of the current impulses for the rotation of the line selector, from the long distance subscriber station a 50 special combination of current impulses will be sent temporarily, said combination consisting therein that the current for A₂ will still be maintained for a certain while, the circuit of B₂, however, being simultaneously 55 interrupted. Accordingly contact 48 of B₂ and contact 49 of A₂ will be closed so that the circuit for the relay C₂ will now be established over ground, battery, contacts 33, windings 1 and 2 of relay C₂, relay F, con-

tacts 49, 48 and 33, resistance w, ground and 65 21, c'', c' 12, E, 15 and ground. In the former circuit F will be excited and C₂ will remain further excited in series with F. The relay F opens its contact 21 and thereby 70 switches off the relay E while it will prepare on the one hand by closing the contacts 21', 52 and 53 a control circuit for keeping the relay C₂ and F in working position, and on the other hand establish the circumventing path P over the line d for through-connection. The relay F opens its contact 50 and therewith prevents a circuit for a testing relay P of the line selector from being eventually established, which circuit is otherwise closed when employing the line selector for 75 local connections. Furthermore the relay F will open its contact 51 and therewith prevent the releasing of the line selector which will occur after relay C₂ is deenergized and contact 36 closed when employing the line 80 selector for local connections.

The testing of the local subscriber line called for from the trunk line office will now be done by means of a testing relay Pa and Pb of the set of relays RS. For testing 90 three conditions of the line called for must be distinguished; this line may be free or occupied, the latter being the case if the subscriber called for is carrying on a local or long distance conversation. In the former case the existing connection may be separated in favor of a long distance connection, to the latter case, however, this does not apply. For each of these three conditions a separate signal, for instance, in form 95 of different buzzers must be provided.

The switching operations in testing the desired line are as follows:

First condition—the desired line is free: After deenergizing the relay E of the group 105 selector III.GWF its contact 27' closes and the winding of the relay X is connected over this contact with the grounded line a, this latter relay will be excited over battery, 25, 27, 14 and ground as the windings 1 and 3 of the relay B₁ and wk₂ at the group selector 110 III.GWF and relay A₂ at the line selector are still excited. The relay A₂ is maintained in energized condition over the contacts 62 and 62' instead of contact 27. Relay X 115 closes its contacts 55, 58 and 68 whereby over contact 55 a current impulse for the testing relay Pa will be generated in the circuit made over ground, Pa, 55, 61, the fourth 120 arm of the long distance group selector III.GWF, line d, the third arm of the line selector to battery and ground at the pre-selector of the desired subscriber. The battery at the pre-selector is disconnected, if the desired subscriber line is occupied. The 125 excited relay Pa opens its contact 61 and thereupon switches itself over its contact 80 into a holding circuit over ground, battery,

24, (relay B_1), 65, 80, P_a and ground. The relay P_a furthermore connects over its contacts 61' the testing relay P_b with the line d . This relay will now also be excited over 5 ground, P_b , d and battery at the pre-selector of the desired subscriber line and thereupon will maintain its excitation over its contact 65' and the contact 24 of relay B_1 . Upon closing contact 65' also the contact 65 will 10 be instantly interrupted, after 65' is already closed. By the opening of contact 65 the circuit for P_a will be interrupted and therewith this relay deenergized. The relay P_b further closes its contact 64 whereby line d 15 is immediately connected to ground. By this also the holding circuit prepared over the contact 21' for the relays C and F will be closed, as their circuit upon reexciting the relay B_2 at the closing of the line loop 20 is interrupted over 49, 48, 32, w and ground and at the same time prevents the relays P_a , P_b of another set of relays RS or the relay P of another line selector LW from making a local connection (contact 50 of F 25 open). The line of the desired subscriber therefore will be locked for other connections, and this for local as well as for long distance service. Relay P_b has further its contacts 66, 71 and 72 closed. Thereby the 30 circuit for the relay L will be closed over ground, battery, L, 68, 66 and ground. Now, a circuit will be established over the working contact 57' of the relay L as follows: ground, buzzer, F_r , 57', 58, translator winding, contact 25, battery and ground. The current of the buzzer F_r flowing in this circuit will be inductively transmitted upon the line a and over the latter to the receiver of the operator at the trunk line office. By this 40 the operator will be notified that the desired line is free, whereupon the desired connection may be completed. If the relay L responds over the contact 70 and 81 thereof, a calling current will be sent into the line a'' , b'' , said current flowing over contacts 71 and 72 of the excited relay P_b , over the line selector LW and contacts 52, 53 of the excited relay F into the desired line, thus effecting the call for the desired subscriber. 45 The responding of relay L and therewith the call of the desired subscriber may be made by repeated sending of the combination of current impulses from the long distance subscriber station. If the desired subscriber 50 thereupon answers, the line loop will be closed upon taking off the receiver of the called subscriber over a'' , b'' and therewith the relay S positioned in the loop at the group selector III.GWF will respond over 55 22, battery and ground. This relay will disconnect at 74 and 75 the relay X from the talking line and the talking connection is made over the contact 13 and 14 at the group selector III.GWF, translator S_p at the set 60 of relays RS and over the contacts 52, 53 at 65 the line selector LW. The relays P and U at the line selector are not excited in this case.

Second condition—the desired line is occupied by a local call: In this case after the 70 excitation of the relay X at the set of relays RS only the testing relay P_a can respond, as in case the local subscriber which is desired for the long distance connection has been the calling party at his pre-selector the 75 low resistance winding of a separating relay is switched into the testing line. On the other hand, if the desired subscriber for the long distance connection has been called for by the existing local connection, then at the 80 line selector LW of the existing local connection the low resistance winding of the testing relay for this line selector will be switched into the testing line. The relay P_a at the set of relays RS is also of low resist- 85 ance and in being connected to the testing line d for the desired subscriber it obtains current sufficient to respond. The testing relay P_b is of high resistance and on being switched into the line d over 61' will be 90 passed by current which is not sufficient for its excitation. Consequently relay L will not respond. The excited relay P_a thus makes up the circuit for the buzzer OV at the contact 56' over ground, OV, 56', 58, 25, 95 battery and ground, the noise of the buzzer being inductively transmitted upon the line a and over this to the receiver of the operator at the trunk line office. The operator, now, will interrupt the existing local connection 100 and then make the long distance connection, whereupon the relay P_b will respond. Said relay is connected over 64 and ground to the line d so that now the holding current for 105 the relays F and C will be closed, therewith also the desired line will again be locked for any other connections. The excited relay C₂ by keeping contact 36 open, will prevent the release magnet M₂ from responding over 110 ground, battery, M₂, 36, p , k_a and ground, and therewith also the line selector LW from being released. The excited relay F, on the other hand, by keeping the contact 51 open, will prevent the closing of a circuit of the 115 counting relay of the interrupted local connection and therewith also the counting of this local connection having been prematurely interrupted in favor of the long distance connection.

For releasing a long distance connection 120 which has been made over group selector III.GWF, set of relays RS and line selector LW the circuits existing over a , b , c will be interrupted at the trunk line office. Therewith B_1 at the group selector III.GWF will 125 become inoperative and open contacts 13 and 14. Furthermore contact 17 will be closed by B_1 and therewith the release mag-

net M_1 of III.GWF will be excited over ground, battery, M_1 , 19', 17, k_3 and ground, said magnet bringing the group selector III.GWF back to its position of rest, the circuit for M_1 being automatically interrupted at k_3 . At the release of the group selector III.GWF by the magnet M_1 the switching arms of the same leave the contacts leading to the line selector LW. Thereby also the circuit for the relay C_2 and F over the contact 64 and line d will be interrupted, thus rendering free the line of the subscriber called for, C_2 at the same time will close over contact 36 the circuit for the release magnet M_2 over ground, battery, M_2 , 36', k_2 , p , k_3 and ground, said magnet releasing the line selector LW. As soon as this latter moves back into its position of rest at k_3 the circuit for M_2 will be automatically interrupted. Also all other switching instrumentalities which have formerly been operated at this moment will return into their position of rest.

Third condition—the desired line is occupied by a long distance connection: In this case at the set of relays RS of the existing long distance connection the relays Pb will be excited and its contact 64 closed. The testing relays Pa and Pb of the set of relays RS at the time testing the desired line can in this case not respond because of the current being withdrawn therefrom over 64 of the relays RS engaging the connection. Accordingly at this set of relays after excitation of relay X a circuit over ground, battery, 58, 57, 56, FV and ground for the buzzer FV will be closed and the operator at the trunk line office will be notified by its buzzing that a long distance connection has already been established, therefore rendering the desired long distance connection temporarily not possible and requiring the desired line to be called up later.

In Fig. 4 in the circuit at the long distance subscriber station F a numeral sender Z is provided which is so constructed that after its adjustment first the current impulses for adjusting the group selectors I.GW, II.GW, III.GW will be generated and thereupon also the current impulses for adjusting the line selector LW, which like the aforesaid group selector, are inserted into the preliminary conditions whereby, however, the testing and all succeeding switching procedures will be suppressed by the adjustment of the line selector LW for ordinary local connections. From the dial switch by means of a combination of current impulses, which can only be made at F, a call seeker AS will thereupon be energized, the way back to the trunk line office (circumventing connection) over AS being, however, different from that by which the desired line has been reached. Thereupon by the numeral sender the cur-

rent impulses for adjusting the selectors for the circumventing connection are also given automatically without any manual steps on the part of the operator, such as pressing a key, because the dial switch Z is individually attributed to the respective long distance subscriber station. Therefore the numeral sender will give always the same definite current impulses for adjusted numbers for the selectors of the circumventing connection such as, for instance, those which correspond to the number of the long distance subscriber line. The operator, now, makes the long distance connection over line selector LW call seeker AS and line selector LW₁, the connection over I.GW II.GW, III.GW being at the same time released.

For exciting the call seekers AS the same combination of impulses may be used as for adjusting the line selector LW, said combination existing during the excitation of the relay A₂, the relay B₂ being at the same time inoperative, as shown in Fig. 4*.

Thereby the circuit for the starting relay A_n, E₄, b_2 , a_n , and ground is closed over a working contact a_2 of the relay A₂ and a back contact b_2 of the relay B₂. If, therefore, the contacts a_2 , b_2 are simultaneously closed, then the relay A_n and the relay E₄ inserted in the same circuit will be excited. The relay A_n closes over its working contact a_n the circuit for a relay R belonging to a free call seeker, this circuit being made from ground, battery, A_n, a_n , R, p_2 and ground, while a holding circuit for A_n and E will be formed over the working contact e of the relay E₄ as follows: ground, t_1 , e_1 , E₄, A_n, battery and ground. Over the working contact r_1 of the relay R, the circuit for the rotary magnet will be closed over ground, battery, interrupter, r_1 , D, p_3 and ground, causing the switching levers of the call seeker to rotate until it will contact with the respective line. In this instant the test relay P will respond over the lever for the test switch and the c-strand, a circuit being formed over ground, battery, r_2 , P, T, e_2 and ground, said test relay short-circuiting its high resistance winding over its working contact p_1 , whereby the separating relay T will respond, a circuit being formed over ground, battery, p_1 , P, T, e_2 and ground. At the same time the line will be through-connected over the working contacts P₁ and p_2 of the test relay P. The excited separating relay T will switch itself into a holding circuit over its front contact t_2 and ground and will interrupt at its back contact t_1 the holding circuit for the starting relay A_n. By this also at the working contact a_n the circuit for the relay R which has been already opened at p_2 will be interrupted and the relay R will open at R₁ the circuit of the rotary magnet which has been discon-

nected at p_3 . Thereby the call seeker AS will be brought to rest.

In Fig. 5 the circumventing connection, forming a new path according to this invention is shown, which in contradiction to well known arrangements, leads to a different place of the preliminary connection than that from which the long distance connection is prepared. Thus the new connections made may lead to special places such as FP in Fig. 6 which are arranged separately from the places with which the numeral senders Z are associated. These FP places as shown in Fig. 6 may be positioned in the same room with the places of the numeral senders, or they may also be installed in other rooms or buildings. Conversation between these places for the numeral senders with the F-places may be carried on over office lines provided especially for this purpose or in any other desired manner.

In Fig. 6 an arrangement is shown, whereby it is assumed that a B-place for the numeral senders is provided in common for several long distance places FP each containing a jack for an operator's cord as shown in Fig. 4. From the numeral sender B, in order to connect with the desired local subscriber T, a connection may be made over pre-selectors VW₁, VW₂, I.GW, II.GW, III.GWF, said selectors belonging all to the trunk line office, and over the line selector LW serving also for the local connections and therefore belonging to the local office. A set of relays RS, Fig. 2, is again associated with the selector III.GWF. After the aforesaid selectors have been adjusted upon the desired line, a new way, namely the circumventing connection will be established over the call seeker AS and a special selector LW₁ for long distance places FP. This connection, for instance, may be made over AS and LW₁ by sending after the adjustment of the selectors VW₁, VW₂, I.GW, II.GW, III.GWF and LW a current impulse from the B-place over the line of these selectors, said current exciting the call seekers AS for adjustment upon this line. Now, after the operator at the B-place has found a free long distance subscriber line, for instance over special office lines or the like, from the B-place through the numeral sender located at this place current impulses will be sent to the selector LW₁, said impulses adjusting said selector upon said found free long distance subscriber line. Thereupon the pre-selectors and group selectors may be released so that the long distance call proper is accomplished only over one long distance place F, selectors LW₁, seekers AS and subscriber selector LW, while the other selectors become free for preparing other long distance connections. By such arrangement with

separate places for impulse signaling and long distance places a great saving is obtained in the number of numeral senders.

In Fig. 7 I have shown a connection of a B-place over the selector I.GW, II.GW, III.GWF with subscribers T of a local office, in which pre-selectors VW are associated with the subscriber lines. From these free selectors lines in multiple connection are led over one or more switches AS to the trunk line office. If, now, a connection is existing between one of the subscribers T with another subscriber of the local office, and if to this existing local connection a long distance connection is added through the B-place, then special switching procedures will take place which will be more fully explained by means of the diagram shown in Fig. 8.

In Fig. 8, each pre-selector VW of the subscriber designated with Sp and corresponding to the subscriber T of Fig. 7 contains besides the testing or separating relay T and the call relay R a resistance w and a special switching arm d. With the contacts of the pre-selector a number of lines are connected in the usual manner leading to the local office. Those contacts of the pre-selector VW which correspond at the switching arm d to the connecting contacts of the lines leading to the local office, are connected with one another and the connecting line c' originating from this common connection of the contacts is used as a testing line back to the B-place. The connection of this place with the desired subscriber station Sp may also be established over pre-selectors, group selectors and a line selector LW, such selectors being shown at I.GW, II.GW, III.GWF and LW in Fig. 8 of the drawings. For this purpose at the B-place after having made the connection to the desired subscriber station Sp, the release of the selectors of this existing local connection is effected in the manner above described for Figs. 2 and 3 without, however, releasing the selector VW. In this case the relay R of the pre-selector VW by impressing proper potentials upon the line a, b at the B-place will be kept excited, while the relay T of the pre-selector VW will be temporarily short-circuited by impressing a proper potential (ground) upon the line c' at the B-place, and therewith made inoperative. By this the rotary magnet D of the pre-selector VW will be excited over ground, battery, D, r, t₁ and ground, said magnet rotating the switch levers of VW until the relay T will respond again and interrupt the circuit of the rotary magnet at t₁ and that of relay R at t₂ and t₃, that is to say, as soon as the testing switch of the pre-selector VW contacts with a line leading to the trunk line office F,

The grounding of a line leading to the trunk line office is made at the long distance place F which is noted by the operator at the B-place as being free and which is destined 5 for the desired long distance connection.

- 5 In order to again disconnect a long distance connection according to the arrangement of Fig. 8, the relay T which has switched off the relay R of the pre-selector 10 VW is made inoperative, whereupon relay T will again connect said relay R to the line and the selector will be brought into its position of rest as R switches the magnet D into circuit.
- 15 In Fig. 9 I have shown a scheme for long distance connections with local subscribers T, whose lines are connected at the local office with call seeker contacts and led over first and second call seekers 1.AS and 2.AS, 20 instead of being connected to the pre-selector as shown in Fig. 8. The connections of some of the second call seekers 2.AS lead to the trunk line office F, while the connections of the other second call seekers 2.AS are connected to the local office O.
- 25 By means of call seekers AS₃, as shown in Fig. 10, the connection to the local subscribers is accomplished from the long distance subscriber station of the trunk line 30 office F. For making a connection from a B-place with the local connection, only the B-place and a subscriber selector LW is indicated. The subscriber selector LW corresponds to LW of Fig. 3. These connections 35 are made in the above described manner for the arrangement according to Figs. 2 and 3. In order to disconnect the existing local connection in favor of the desired long distance connection the operator of the B-place 40 again impresses proper potentials upon the line *a* and *b*. Besides at the B-place the *c*-line will be temporarily connected to the battery by means of the key *tc*. Accordingly the relays A₃ and P₃ will respond, a 45 circuit being formed over ground, battery *tc*, t₄', P₃, A₃ and ground. The relay P₃ which will be excited thereby, now connects over its contact p₃ the relay T₃ to the testing contacts of the call seeker AS₃ over a 50 circuit formed by ground, battery, p₃, T₃, t₃, V₂, m₃, C₃, w₁ and ground. The relay A₃ switches the relay R₃ of the call seeker AS₃ into circuit over ground, battery, a₃, R₃, v₂ and ground, which thereupon switches the 55 rotary magnet D₃ of the call seeker AS₃ into circuit, a circuit being formed over ground, interrupter, D₃, v₂', r₃, a₃, battery and ground. The arms of the call seeker AS₃ are thereby rotated until they contact with 60 the line to the relay T₃. Thereupon the relays T₃, V₂, and C₃ are excited. V₂ interrupts at t₄, t₄' the circuit of P₃ and A₃ which latter will deenergize the relay R₃ at a₃. Furthermore T₃ will close over its working 65 contact t₃ a holding circuit of its own, this

circuit being formed over ground, battery P₄, t₃, V₂, m₃, C₃, w₁ and ground. In this circuit the low resistance relay P₄ will not respond and relays T₃, V₂ and C₃ will be further kept excited.

70

If, however, at the long distance subscriber station which has been found free by the operator of the B-place and which has been notified by the operator of the desired long distance connection, the key *t* will 75 be depressed and therewith a resistance *wi* inserted in the circuit of V₂, T₃ and P₄ will be short-circuited, then also P₄ will obtain sufficient current for responding. P₄ then opens at p₄ the circuit for the relay T₂ at 80 the call seeker AS₁, V₁ at the call seeker AS₂, and C at the first group selector at the local office O. By this, now, the selector of the existing local connection will be released, at the same time the call seeker AS₂ 85 will be made free. Furthermore P₄ will close the contact p₅ over which the excitation of the relay T₁ of the call seeker AS, which relay T₁ is excited during the existing local connection, will be further kept 90 excited without any interruption, so that now the call seeker AS₁ will also be operated for a long distance connection which has just been established.

95

The relay T₂ when responding, will keep open the circuit for the rotary magnet D₁ of the call seeker AS₁ by means of the contact t₄, so that if P₄ responds by opening contact p₄ which causes the relays T₂ and V₁ and C to be deenergized by closing the 100 contact t₂ of the relay T₂, the call seeker AS₁ will therefore be prevented from being further rotated.

105

In order to disconnect this long distance connection, the circuit for T₂ will be interrupted at the trunk line office, for instance by depressing a key m₃, whereby the relays C₃, T₃, P₄ and T₁ will be made inoperative and the seekers AS₁ and AS₃ again be ready for making new connections.

110

Having thus described my invention I claim as new and desire to secure by Letters Patent of the United States:—

1. In a telephone exchange system, subscribers' lines, switches for establishing a preliminary connection between a calling line and a called line, other switches for establishing a talking connection between said calling and said called line, impulse generating means for controlling said first 115 switches, other impulse generating means for controlling said second switches, said second impulse generating means being arranged to send impulses in addition to the impulses of said first impulse generating 120 means.

125

2. In a telephone exchange system, subscribers' lines, switches for establishing a preliminary connection between a calling line and a called line, other switches for 130

- establishing a talking connection between said calling and said called line, impulse generating means for controlling said first switches, other impulse generating means 5 for controlling said second switches, said second impulse generating means being arranged to send impulses in addition to the impulses of said first impulse generating means, both said impulse generating means 10 being components of one apparatus.
3. In a telephone exchange system, subscribers' lines, switches for establishing a preliminary connection between a calling and a called line, other switches for establishing a talking connection between said calling and said called line, manually adjustable impulse generating devices for controlling said first switches, another impulse generating device associated with said preliminary connection and automatically sending out impulses for controlling said second switches.
4. In a telephone exchange system, subscribers' lines, trunk lines less numerous than said subscribers' lines, switches for establishing a preliminary connection with one of said subscribers' lines, other switches for establishing a talking connection with said desired line, impulse generating devices for controlling said first switches, another impulse generating device for controlling said second switches, said talking connection being branched off from one of said trunk lines, said second impulse generating device being associated with said preliminary connection.
5. In a telephone exchange system, subscribers' lines for ordinary and preferred service, calling stations for preferred service, switches for establishing connections for ordinary service, means for establishing a preliminary connection with one of said subscribers' lines over said switches for ordinary service, other switches for establishing a preferred connection between said one of said subscribers' lines and one of said preferred calling stations.
6. In a telephone exchange system, subscribers' lines for ordinary and preferred service, calling stations for preferred service, switches for establishing connections for ordinary service, means for establishing a preliminary connection with one of said subscribers' lines over said switches for ordinary service, other switches for establishing a preferred connection between said one of said subscribers' lines and one of said preferred calling stations, and an impulse generating device for controlling said preliminary and said preferred connections, said impulse generating device being associated with said preliminary connection.
7. In a telephone exchange system, subscribers' lines, switches for establishing ordinary and preferred connections between 15 said subscribers' lines, impulse generating devices for establishing a preliminary connection with a desired one of said subscribers' lines over said switches for establishing ordinary connections, and other impulse generating means controlling said switches for preferred connections, said other impulse generating means being arranged to send impulses in addition to the impulses of said first impulse generating device.
8. In a telephone exchange system, subscribers' lines, switches for establishing preliminary connections with said subscribers' lines, other switches for establishing a talking connection with said subscribers' lines, impulse generating devices for controlling said first switches, other impulse generating means controlling said second switches, said other impulse generating means being arranged to send impulses in addition to the impulses of said first impulse generating device, circuits for releasing said preliminary connections, and other circuits for releasing said talking connections.
9. In a telephone exchange system, subscribers' lines, switches for establishing ordinary and preferred connections between said subscribers' lines, impulse generating devices for establishing said ordinary connections over contacts of said switches, and other impulse generating means sending impulses in addition to the impulses of said first impulse generating device for establishing said preferred connections over other contacts of said switches.
10. In a telephone exchange system, subscribers' lines, switches for establishing ordinary connections between said lines, operators' places for establishing preferred connections with said lines, said preferred connections being preceded by a preliminary connection with said lines, an impulse generating device for establishing said preliminary connection, and another impulse generating device sending impulses in addition to the impulses of said first impulse generating device for establishing said preferred connection.
11. In a telephone exchange system, subscribers' lines, switches for establishing ordinary connections between said lines, operators' places for establishing preferred connections with said lines, said preferred connections being preceded by a preliminary connection with said lines, an impulse generating device for establishing said preliminary connection over said switches provided for said ordinary connections, and another impulse generating device sending impulses in addition to the impulses of said first impulse generating device for establishing said preferred connection.
12. In a telephone exchange system with calling stations for ordinary and preferred

- service, the combination of subscriber selectors for preferred service, instrumentalities for making a preliminary connection with such subscriber selector, selecting means permitting a back-selecting from a line of this preliminary connection, preferred service devices for such subscriber selector, a generator of additional impulses for operating said devices from the calling station, and 10 reserving means for engaging the subscriber selector.
13. In a telephone exchange system for ordinary and preferred service, the combination of subscriber lines, with subscriber selectors for preferred service, instrumentalities for making a preliminary connection with such subscriber selector, means permitting back-selecting from a line of this preliminary connection, said means consisting 15 of a selector controlled from a calling station, subscriber selectors for making connections with said subscriber lines, special selectors for establishing preferred connections with the subscriber selectors, and controlling 20 devices for preferred service, said controlling devices being associated with said selectors.
14. In a telephone exchange system for ordinary and preferred service, the combination of subscriber selectors, with subscriber lines and exchanges, instrumentalities for making a preliminary connection with a subscriber selector in case of preferred service, means permitting a back-selecting from a line 25 of said preliminary connection, said means consisting of a selector controlled by a preferred subscriber when calling, and apparatus for making the talking connection, said apparatus being associated with the 30 selector for preferred service.
15. In a telephone exchange system for ordinary and preferred service, the combination of subscriber stations, with subscriber select 35 s, circuits for making preliminary connections with such subscriber selector in case of preferred service, selecting means and controlling means therefor actuated from a subscriber station for preferred calls and permitting back-selecting from a line 40 of this preliminary connection, subscriber selectors for ordinary connections, special controlling device therefor, second selectors associated with the former for establishing 45 connections with subscriber selectors for preferred calls, and special circuits for operating said second selectors, said circuits being 50 separate from the circuit for the ordinary connections.
16. In a telephone exchange system for ordinary and preferred service, the combination 55 of subscriber stations, with subscriber selectors, switching instrumentalities for long distance service, talking wires, means for making preliminary connection with a subscriber selector in case of preferred serv- 60 ice, selecting means permitting back-selecting from a line of this preliminary connection and controlling means therefor actuated from a calling station, means for connecting said switching instrumentalities to the talk- 65 ing wires, and a special impulse generator for connection over said talking wires after completion of said preliminary connection. 70
17. In a telephone exchange system for ordinary and preferred service, the combination of subscriber stations, with subscriber selectors, switching instrumentalities for long distance service, talking wires, means for making preliminary connection with a subscriber selector in case of preferred service, selecting means permitting back-selecting from a line of this preliminary connection and controlling means therefor actuated from a calling station, means for connecting said switching instrumentalities to said talking wires, a special impulse generator for connection over said wires after completion of said preliminary connection, and means for through-connecting and clearing out the talking line. 75
18. In a telephone exchange system for ordinary and preferred service, the combination of subscriber selectors, stations and lines, with instrumentalities for making a preliminary connection with a subscriber selector in case of preferred service, selecting means and controlling means therefor actuated from a station for making a preferred call and permitting back-selecting from a line of this preliminary connection, 80 subscriber selectors for making ordinary connections with the subscriber lines, special controlling devices for long distance service, and a relay provided at the subscriber selector for through-connecting the talking line 85 by a special circuit in case of preferred connections. 90
19. In a telephone exchange system for ordinary and preferred service, the combination of subscriber selectors, lines and stations with instrumentalities for making a preliminary connection with a subscriber selector for preferred service, means permitting a back-selecting from a line of this preliminary connection, means for sending a 95 controlling impulse from a calling station to a subscriber selector, and further means for transmitting said impulse backwardly upon the means for back-selecting. 100
20. In a telephone exchange system for ordinary and preferred service, the combination of subscriber selectors, lines and stations with controlling devices for preferred service connections, instrumentalities for making a preliminary connection with a subscriber selector in case of preferred service, means permitting a back-selecting from a line of said preliminary connection said means consisting of a selector controlled 110 from a preferred calling line, switching in- 115

- strumentalities for making the talking connection, a controlling device for preferred service associated therewith, means for sending a controlling impulse from the preferred calling station to the subscriber selector, and further means for transmitting said impulse back upon the selector of the back connection.
21. In a telephone exchange system for ordinary and preferred service, the combination of subscriber selectors, with special switching devices therefor, subscriber lines and station and circumventing lines, operator's places, subscriber selectors for preferred service, instrumentalities for making a preliminary connection with a subscriber selector for preferred service, means permitting a back-selecting from a line of this preliminary connection, said means consisting of a selector and controlling means therefor actuated from an operator's place, second subscriber selectors for making ordinary connections with the subscriber lines, special controlling devices therefor, special circuits for operating said second selectors separate from the circuits for the ordinary connections, and a current impulse generating device adapted to be operated by a preferred calling station, said generating device being capable of giving automatic current impulses for adjusting the selectors of the preparatory connection and for causing the special switching devices to coöperate with said second subscriber selectors and for adjusting thereupon also the selectors of the circumventing connection.
22. In a telephone exchange system for ordinary and preferred service, the combination of subscriber selectors, with special switching devices therefor, subscriber stations, connecting lines, and talking wires, means for making preliminary connection with a subscriber selector in case of preferred service, selecting means permitting back-selecting from a line of this preliminary connection and controlling means therefor actuated from the calling station, switching apparatus for long distance service, connections between said apparatus and the talking wires, so as to make said wires operatively inserted after completion of a preliminary connection by a proper current impulse from the calling line, means for through-connecting and clearing out the talking wire, and a current impulse generating device adapted to be operated by a preferred calling station, said generating device being capable of giving automatic current impulses for adjusting the selectors of the preparatory connection and for causing said special switching devices to coöperate with said subscriber selectors and for adjusting thereupon the selectors of the circumventing connection.
23. In a telephone exchange system for ordinary and preferred service the combination of subscriber selectors, subscriber lines, instrumentalities for making a preliminary connection with a subscriber selector in case of preferred service, selecting means and controlling means therefor actuated from the preferred calling line and permitting back-selecting from a line of this preliminary connection, special controlling devices, a relay provided at each of the subscriber selectors for through-connecting the talking line by a special circuit in case of preferred connection, and a current impulse generating device adapted to be operated by a preferred calling station, said generating device being capable of giving automatic current impulses for adjusting the selectors of the preparatory connection and for causing the special controlling devices to coöperate with said subscriber selectors and for adjusting thereupon also the selectors of the circumventing connection.
24. In a telephone exchange system for ordinary and preferred service, the combination of subscriber stations and lines and trunk lines with subscriber selectors for ordinary connections, special controlling devices therefor, operator's places, instrumentalities for making a preliminary connection with a subscriber selector for preferred service, means permitting a back-selecting from a line of this preliminary connection, said means consisting of a selector and a controlling device therefor actuated from an operator's place, special circuits for operating said selectors separate from the circuits for the ordinary connections, and a current impulse generating device adapted to make automatically a circular back-connection at a calling station, switching devices for connecting the lines which originate from said calling station, and separate switching devices for the incoming lines at the station thereof for connecting the same with the trunk lines.
25. In a telephone exchange system for ordinary and preferred service the combination of trunk lines, talking wires, subscriber stations, with lines and selectors, means for making preliminary connection with a subscriber selector in case of preferred service, selecting means permitting back-selecting from a line of said preliminary connection and controlling means therefor actuated from the calling end, switching instrumentalities for long distance service connected to the talking wires, so as to make said wires operatively inserted after completion of a preliminary connection by a special current impulse from the calling line, means for through-connecting and clearing out the talking wire, and a current impulse generating device capable of making automatically a back-connection at a calling station, switching devices for con-

- necting the lines which originate from said subscriber calling station, and separate switching devices for the incoming lines at the end thereof for connecting the same with the trunk lines. 5
26. In a telephone exchange system for ordinary and preferred service, the combination of local or long distance lines and stations, with special B-places provided in 10 addition to said stations, subscriber selectors, instrumentalities for preferred service capable of making preliminary connection with one of said subscriber selectors, means permitting back-selecting from a line of this 15 preliminary connection, lines for engaging the subscriber selectors which originate from said B-places and lead to the selectors for the local connections, and lines for making the talking connections ending at said long 20 distance stations themselves.
27. In a telephone exchange system for ordinary and preferred service, the combination of local and long distance lines and stations, with special B-places provided in 25 addition to said stations, subscriber selectors, operator's places, instrumentalities for making a preliminary connection with a subscriber selector for preferred service, selecting means permitting a back-selecting 30 from a line of this preliminary connection and controlling means therefor actuated from an operator's place, lines for engaging the subscriber selectors, said lines originating from said B-places and leading to the 35 selectors for the local connections, and other lines for making the talking connections ending at said long distance stations.
28. In a telephone exchange system for ordinary and preferred service, the combination 40 of a trunk line office, with subscriber stations, special B-places provided in addition to said stations, subscriber selectors, instrumentalities for preferred service adapted to make preliminary connection with a subscriber selector, means permitting a back-selecting 45 from a line of this preliminary connection, said subscriber selectors being adjustable over lines originating from said B-place upon contacts of the line leading to 50 a desired station, connections between the subscriber selectors and the trunk line office for the purpose of circumventing switching procedures following the adjustment of the subscriber selector. 55
29. In a telephone exchange system for ordinary and preferred service, the combination of a trunk line office with subscriber stations, special B-places provided in addition to said stations, subscriber selectors, operator's places, instrumentalities for making 60 a preliminary connection with a subscriber selector for preferred service, selecting means permitting a back-selecting from a line of this preliminary connection and con-
- trollable from one of said operator's places, 65 said subscriber selectors being adjustable over the lines originating from the B-place upon contacts of the line leading to the desired station, and connections between the aforesaid subscriber selectors and the trunk 70 line office for the purpose of circumventing switching procedures following the adjustment of the subscriber selector. 75
30. In a telephone exchange system for ordinary and preferred service, the combination of subscriber stations and lines, with special B-places provided in addition to 80 said stations, subscriber selectors, instrumentalities for making a preliminary connection with a subscriber selector for preferred service, means permitting a back-selecting from a line of this preliminary connection, said means consisting of a selector controlled from an operator's place, special controlling devices for the subscriber 85 selectors making ordinary connections with the subscriber lines, separate circuits for operating said selectors, said subscriber selectors being adjustable over the lines originating from the B-places upon the contacts of the line leading to the desired subscriber station, and connections between the subscriber selectors and the trunk line office for the purpose of switching procedures 90 following the adjustment of the subscriber 95 selector. 100
31. In a telephone exchange system for ordinary and preferred service, the combination of a trunk line office, with subscriber lines and selectors, instrumentalities for preferred service adapted to establish a preliminary circuit with a subscriber selector, means permitting a back-selecting from a line of this preliminary connection, a pre-selector and controlling means therefor actuated by said preliminary circuit, a special contact for establishing the talking connection between the desired line and the trunk line office, and means for adjusting said 105 pre-selector upon said contact. 110
32. In a telephone exchange system for ordinary and preferred service, the combination of subscriber lines, with subscriber selectors, operator's places, a trunk line office, instrumentalities for establishing a preliminary circuit with a subscriber selector for preferred service, selecting means permitting a back-selecting from a line of this preliminary connection and controlling 115 means therefor actuated from an operator's place, a pre-selector controllable by the aforesaid preliminary circuit, a special contact for establishing the talking connection between the desired line and the trunk line office, and means for adjusting said pre-selector upon said contact. 120
33. In a telephone exchange system for ordinary and preferred service, the combi-

- 3 nation of subscriber lines, with subscriber 65
selectors, operator's places, a trunk line
office, instrumentalities for making a pre-
liminary connection with a subscriber selec-
tor for preferred service, means permitting
a back-selecting from a line of this prelimi-
nary connection, said means consisting of a
selector and controlling means therefor actuated
from an operator's place, special con-
trolling devices for said subscriber selectors
making ordinary connections with the sub- 70
scriber lines, and separate circuits for oper-
ating said selectors, a pre-selector controlled
by the aforesaid preliminary circuit, a spe-
cial contact for establishing the talking con-
nection between the desired line and the 75
trunk line office, and means for adjusting
said pre-selector upon said contact.
34. In a telephone exchange system for
20 ordinary and preferred service, the combi-
nation of subscriber lines, with subscriber
selectors, a trunk line office, instrumentalities
for making a preliminary connection with a
subscriber selector in case of preferred serv- 80
ice, means permitting a back-selecting from
a line of said preliminary connection, said
means consisting of a selector and control-
ling means therefor actuated from a preferred
line, switching means for making the talk- 85
ing connection, a controlling device for the
connection for preferred service associated
with said switching means, a pre-selector
controllable by the aforesaid preliminary
circuit, a special contact for establishing 90
the talking connection between the desired
line and the trunk line office, and means
for adjusting said pre-selector upon said
contact.
35. In a telephone exchange system for
40 ordinary and preferred service, the combi-
nation of a trunk line office, with sub-
scriber lines and selectors, preferred service
connections capable of making a preliminary
circuit with a subscriber selector, means per- 95
mitting a back-selecting from a line of this
preliminary circuit, first, second, third, and
subsequent selectors, said first selectors be-
ing controlled from said preferred service
connections, said second, third, and subse- 100
quent selectors being controlled from said
first selectors for subsequent connection with
the trunk line office, said first selectors being
in series with said second, third and subse- 105
quent selectors.
- 55 36. In a telephone exchange system for
ordinary and preferred service, the combi-
nation of a trunk line office, with subscriber
lines, subscriber selectors, preferred service
connections capable of making a preliminary 110
circuit with a subscriber selector, means per-
mitting a back-selecting from a line of this
preliminary circuit, said means consisting
of a selector controlled from said trunk line 115
office, special controlling devices for the sub-
scriber selectors for ordinary connections 65
with the subscriber lines, separate circuits
for operating said selectors for preferred
service, first selectors being controlled from
the circuit for preferred service, second, 70
third and subsequent selectors in series with
said first selectors, said second, third, and
subsequent selectors being controlled by said
first selectors for the subsequent connection
with the trunk line office.
37. In a telephone exchange system for 75
ordinary and preferred service, the combina-
tion of circuits for ordinary and preferred
connections, with subscriber selectors, in-
strumentalities capable of making prelimi-
nary connection with a subscriber selector 80
for preferred service, means permitting a
back-selecting from a line of this prelimi-
nary connection, special second selectors, one
of said special second selectors controlled
from the circuit for preferred connections 85
and over the subscriber selector at the time
engaged, means for paralleling another of
said special second selectors to the former
special second selector at a time in operation,
and means for releasing only said other spe-
cial second selector and the selectors back
thereof in case of a subsequent separation of
the ordinary connection.
38. In a telephone exchange system for 90
ordinary and preferred service, the combi-
nation of an operator's place, with subscriber
lines and selectors, circuits for ordinary con-
nections, instrumentalities for making a pre-
liminary connection with a subscriber selec- 95
tor for preferred service, means permitting
a back-selecting from a line of this pre-
liminary connection, said means consisting
of a selector and controlling means therefor
actuated from said operator's place, special 100
controlling devices for subscriber selectors
for ordinary connections with the subscriber
lines, special circuits for operating said se-
lectors separate from the circuits for the
ordinary connections, special second selec- 105
tors and means for paralleling one of said
special second selectors to another of said
special second selectors at the time in opera-
tion, and means for releasing only said
parallel special second selector and the selec- 110
tors back thereof in case of a subsequent
separation of the ordinary connection.
39. In a telephone exchange system for 115
ordinary and preferred service, the combi-
nation of subscriber lines and selectors, with
circuits for ordinary and preferred connec-
tions, instrumentalities for making a pre-
liminary connection with a subscriber selec- 120
tor in case of preferred service, means
permitting a back-selecting from a line of
said preliminary connection, said means con-
sisting of a selector controlled from a pre-
ferred calling line, switching instrumentalities
for making the talking connection, a 125

controlling device associated with said switching instrumentalities for preferred connection, a special second selector controlled from the circuit for preferred connections and over the subscriber selector at the time engaged, another special second selector, means for paralleling the other special second selector to the former special second selector at the time in operation, and means for releasing only said other special

second selector and the selectors back thereof in case of a subsequent separation of the ordinary connection.

In witness whereof I have hereunto set my signature in the presence of two subscribing witnesses.

GEORG GRABE.

Witnesses:

WOLDEMAR HAUPT,
HADTWIG O. NEUBAUER.
